COMBINED ARMREST AND SPEAKER UNIT FOR AUTOMOBILES

Charles A. Osberg, 5724 NE. 17th Ave.,
Portland, Oreg. 97211

Filed Jan. 3, 1967, Ser. No. 5,266

Term of patent 14 years

(Cl. D14—6)

Fig. 2.

Fig. 1.

Fig. 3.

FIG. 1 is a front perspective view of the combined armrest and speaker unit for automobiles, showing my new design;

FIG. 2 is a rear perspective view thereof; and

FIG. 3 is an end elevation thereof.

The portion shown in broken lines in FIGURE 3 is included for illustrative purposes only of a segment of a motor vehicle door.

I claim:

The ornamental design for a combined armrest and speaker unit for automobiles, as shown and described.
